LEG ATTACHING DEVICE

Claude C. Bogardus, Warsaw, Ky.

Application July 19, 1932. Serial No. 623,422

7 Claims. (Cl. 45—11)

This invention relates to a leg attaching device designed primarily for use in connection with the legs of card tables, but it is to be understood that a leg attaching device, in accordance with 5 this invention may be employed in any connection for which it may be found applicable, and the invention has for its object to provide, in a manner as hereinafter set forth, a device of the class referred to for setting up a wedging action 10 upon the leg when the latter is extended and to detachably maintain the leg in such position.

A further object of the invention is to provide, in a manner as hereinafter set forth, a leg attaching device for pivotally connecting the leg 15 with the table top and including spring controlled releasable means for fixedly securing the leg stationary when the latter is extended.

A further object of the invention is to provide, in a manner as hereinafter set forth, a leg attaching device for pivotally connecting the leg 20 with a table top, and including spring controlled releasable wedging means carried by the leg for fixedly securing the latter in extended position.

Further objects of the invention are to provide, 25 in a manner as hereinafter set forth, a device for the purpose referred to, which is simple in its construction and arrangement, strong, durable, compact, readily installed with respect to a table top, thoroughly efficient for the purpose intended, and comparatively inexpensive to manufacture.

To the above ends essentially, and to others which may hereinafter appear, the invention 35 consists of such parts, and such combination of parts which fall within the scope of the invention as claimed.

In the drawing:

Figure 1 is a fragmentary view in section of a table top showing the adaptation therewith of 40 the leg attaching device in position for maintaining a leg extended, the device being shown in side elevation and the leg broken away.

Figure 2 is a fragmentary view in section of a table top showing the adaptation therewith of 45 the leg attaching device in position for maintaining a leg extended, the device being shown in rear elevation and the leg broken away.

Figure 3 is a fragmentary view in inverted plan of a table top showing the adaptation there- 50 with of the leg attaching device and with the leg in folded position, the device being shown in inverted plan and the leg broken away.

The leg attaching device includes a channeled shaped housing 1 to receive the upper portion of 55 a table leg 2, and the width of the housing rela-

tive to that of the upper portion of the leg is such, that a wedging action will be set up between the sides of the housing and sides of the upper portion of the leg when the latter is extended. A wedging action is also set up between the 60 upper portion of the sides of the leg and the sides of the housing when the leg is folded, but the area of such action is not as great when the leg is extended, and in this connection see Figure 3.

The housing 1 includes a front wall 3 and a 65 pair of side walls 4, 5. The length of the side walls is greater than the width of said front wall. The side walls are the same height and length and the height thereof corresponds to that of the front wall. The bottom edge 7 of 70 each side wall is of less length than the top edge 8 thereof. The end edge 9 of each side wall is extended rearwardly with respect to the rear end of edge 7 and is rearwardly curved from edge 7 to edge 8. The side wall 5 at its 75 top is formed with a laterally extended lengthwise disposed apertured flange 10. The wall 5 has a pair of spaced openings 11 for a purpose to be referred to.

One of the depending ends of table top 12 is 80 indicated at 13. One of the depending sides of top 12 is designated 14. The top 12 is countersunk in the end and side 13, 14 respectively as at 15, 16 respectively. The housing 1 is positioned below the top 12 in a manner whereby 85 front wall 3 will abut the inner face of end 13 and wall 4 will abut the inner face of side 14. Holdfast means 17 extend through wall 3 and engage in end 13. Holdfast means 18 extend through wall 4 and engage in side 14. Holdfast 90 means 19 extend through flange 10 and engage in top 12. The openings 10 in wall 5 permit of access being had to holdfast means 18.

The walls 4, 5 are provided with wedge shaped notches 20, 21 respectively which open at the 95 rear ends of the bottom edges 7 of said walls.

The inner transverse corners of leg 2 are rounded as at 22, 23. Extended through the leg 2 in proximity to its inner or upper end and at a point between its lengthwise median and rear side is a pivot bar 24 therefor which extends through walls 4, 5 and is coupled to housing 1. The ends of bar 24 are headed as at 25. The rear side 26 of leg 2 is formed centrally with a recess 27 extending lengthwise of the leg. The 100 outer end of the recess is open, as at 28.

Positioned against the rear side 26 of leg 2 and slidably relatively to and lengthwise of the latter is a spring controlled latching member 29 for wedging engagement in the notches 20, 21 110

for the purpose of maintaining the leg in extended position. The member 29 is formed of an intermediate part 30 and a pair of end parts 31, 32. The part 30 is of less width and of greater length than part 32, the latter is of greater width and of less length than part 31. The part 31 is of greater length than part 30. The member 29 has a centrally disposed lengthwise slot 33 formed in a portion of parts 31, 32 and extending through part 30. The width of part 32 with respect to part 30 provides a pair of oppositely extending protuberances 33, 34 for wedging engagement in the notches 20, 21 and for riding against the end edges 9 of walls 4, 5. The part 32 has extending outwardly from the free edge and at right angles thereto a flange 35 constituting a finger grip for shifting member 29 against the action of its controlling spring to be presently referred to. The part 31 has extending inwardly from its free edge and at right angles thereto an abutment 36 which slides in the recess 27. Mounted in the recess 27 and interposed between the inner end wall of the latter and the abutment 36 is the controlling spring 37 for the member 29. The spring 37 permanently tends to shift the member 29 in a direction towards the inner end of the leg 2. The member 29 is slidably connected to leg 2 by a plurality of headed retaining elements 38 which extend through slot 33 and are fixed to leg 2 in spaced relation to the inner end wall of recess 27.

The table top 12 has its lower face in proximity to the edges 9 of walls 4, 5 provided with a pocket 39 to receive the flange 35 when the leg is folded.

If the leg 2 be in the position shown in Figure 3, and it is desired to latch it in extended position, the leg is pulled outwardly carrying the latching member therewith and with the protuberances 33, 34 riding against the edges 9 against the action of spring 37. When the protuberances arrive at the open ends of the notches 20, 21 the spring 37 will act to pull the protuberances in the notches thereby positioning member 29 in latching position, and with a wedging action being set up between the protuberances and walls of the notches as well as a wedging action being formed between the upper portion of the leg and walls 4, 5 of the housing. To release the leg, the member 29 is pulled in a direction to provide for the protuberances to clear the notches and to be positioned against edges 9. The leg can then be moved to the position shown in Figure 3, and with spring 37 acting to maintain the leg in folded or non-extended position.

What I claim is:-

1. In a leg attaching device, the combination of a housing adapted to be secured with a table top and formed with an open bottom and an open end, a foldable leg having its upper portion extended into said housing, the width of a part of the housing and to the width of a part of said portion of the leg being such relatively to each other to provide a wedging action between said parts when the leg is folded and extended, means for pivotally connecting said upper portion to said housing, and a spring controlled latching member slidably connected against one side and disposed lengthwise of one side of the upper portion of the leg, said member and housing having coacting interengaging means to provide a releasable wedge-like latching action between said member and housing for maintaining the leg in extended position.

2. In a leg attaching device, a housing for connection with a table top, said housing having an open end and an open bottom, means for pivotally connecting the upper portion of the leg within the housing, a spring controlled slotted latching member positioned lengthwise of and against one side of the upper portion of the leg, the controlling spring for said member being seated in said side and having one end bearing against the inner end of said member, means for slidably connecting said member to the leg, said member provided at its outer end with oppositely disposed lateral protuberances, said housing including side walls having bottom edges, curved end edges and notches at the point of joiner between said end and bottom edges, said notches being for the reception of the protuberances against the action of the controlling spring of said member when the leg is extended to maintain the latter extended, and said protuberances riding against said curved edges against the action of the controlling spring of said member when the leg is folded to maintain the latter folded.

3. In a leg attaching device, a housing for connection with a table top, said housing having an open end and an open bottom, means for pivotally connecting the upper portion of the leg within the housing, a slotted latching member positioned lengthwise of and having its inner end extending into one side of said upper portion, means for slidably connecting said member against said side of the upper portion of the leg, said member provided with oppositely extending spaced aligning lateral protuberances, a controlling spring for said member seated in said side of the upper portion of the leg and bearing at one end against the inner end of said member, said housing including side walls having bottom edges, curved end edges and notches at the point of joiner between said end and bottom edges, said notches being for the reception of the protuberances against the action of the controlling spring of said member when the leg is extended to maintain the latter extended, said protuberances riding against said curved edges against the action of the controlling spring of said member when the leg is folded to maintain the latter folded, said protuberances being arranged at the outer end of said member, and a finger grip at the outer end of the member and arranged at right angles to said protuberances.

4. In a table leg attaching device, the combination of a leg provided with a recess in one side at the upper end of the latter, a slotted latching member disposed lengthwise of said side and provided at its inner end with an angularly disposed abutment positioned in opposed parallel spaced relation to an end wall of the recess, a controlling spring for said member mounted in said recess and interposed between and permanently bearing against said abutment and wall, means extending through the slot of said member for slidably connecting it to said side, said member having its other end formed with lateral protuberances, a housing adapted to be secured with a table top, means for pivotally connecting the upper portion of the leg to and within said housing, and said housing having means for receiving said protuberances against the action of said spring for latching the leg in an extended position.

5. In combination, a table top having its inner face provided with a pocket, a housing secured to said face adjacent to and forwardly of the pocket, said housing being open at its bottom

- and at its inner end, a foldable leg having its upper portion positioned in said housing and with the rear side face of said portion being formed with a recess, means for pivotally connecting 5 said portion of the leg to the housing adjacent said recess, a controlling spring in said recess, said housing including side walls provided with spaced aligning notches, a spring controlled latching member slidably connected upon the said 10 rear side face of said portion of the leg and provided at its outer end with lateral protuberances engageable in said notches for releasably securing the leg in extended position, and at its inner end with an abutment extending into said 15 recess and bearing against one end of said spring, said abutment and protuberances coacting with the controlling spring of said member and the side walls of the housing maintaining the leg folded, said member having a finger grip disposed at right angles to the protuberances and seating in said pocket when the leg is folded, and the width of a part of the housing and the width of a part of said portion of the leg being such relatively to each other to provide a wedging action between said parts when the leg is folded and extended. 80
7. In a leg attaching device, a housing adapted to be secured with a table top and with an open bottom and an open rear end, a foldable leg having its upper portion arranged within and pivotally connected to the housing, the width of a part of said housing and the width of a part of said upper portion being such relatively to each other to provide for a wedging action between said parts when the leg is folded and extended, said housing being formed with V-shaped aligning notches at its rear end, and a spring 100 controlled latching member slidably connected upon the rear side face of said upper portion and provided with protuberances for engaging in said notches for holding the leg in extended position, the thickness of said protuberances with respect to the width of said notches being such to provide in connection with the controlling spring for said member to set up a wedge-like action between opposed walls of the notches and the protuberances when the leg is extended. 90
6. In combination, a table top having its inner face provided with a pocket, a housing secured to said face adjacent to and forwardly of the pocket, said housing being open at its bottom and at its inner end, a foldable leg having its upper portion positioned in said housing and with the rear side face of said portion being formed with a recess, means for pivotally connecting said portion of the leg to the housing adjacent said recess, a controlling spring in said recess, said housing including side walls provided with spaced aligning notches, a spring controlled latching member slidably connected upon the said rear side face 105 of said portion of the leg and provided at its outer end with lateral protuberances engageable 110
